United States Patent Office.

GILBERT J. FERRISS, OF WASHINGTON, DISTRICT OF COLUMBIA, ASSIGNOR
TO HIMSELF AND BYRON SYKES.

Letters Patent No. 64,652, dated May 14, 1867.

COMBINATION TOOL.

The Schedule referred to in these Letters Patent and making part of the same.

Be it known that I, GILBERT J. FERRISS, of Washington, in the county of Washington, in the District of Columbia, have invented a new and improved Combination Wrench, Screw-Driver, Brad-Awl, (or Gimlet,) and Claw-Hammer; and I do hereby declare that the following is a full and exact description thereof, reference being had to the accompanying drawing, and the letters of reference marked thereon.

The nature of my invention consists in the combination of the four above-named articles.

To enable others skilled in the art to make and use my invention, I will proceed to describe its construction and operation.

Figure 1 is a perspective view with screw-driver as set in groove at side of handle.

Figure 2 is a view of the lever dropped into its place and fastened by thumb-screw.

Figure 3 is a view with slide run back to allow the brad-awl (or gimlet) to be raised.

Figure 4 is a view of claw for drawing nails.

Figure 5 is a view of brad-awl (or gimlet) raised up.

I construct the handle, as shown at A in the accompanying drawing, by cutting a groove five-twelfths of an inch deep, half the length on the top; the other half is one-fourth of an inch deep to receive lever B. The hammer C is made to be firmly fastened to handle A. On the end of hammer C is cut groove d, and covered by plate e, for the purpose of drawing nails. The slide F works on handle A, and when used as a wrench is shoved by lever B against hammer C to fit the nut, and lever B is then dropped into the groove and firmly fastened by catch g. When it is desired to be retained in that position turn thumb-screw h. Brad-awl (or gimlet) i is combined by a groove cut in side of handle A, and works on a hinge at end of handle A and under hammer C, when it is required for a brad-awl (or gimlet.) Slide F is run back toward catch g; the brad-awl (or gimlet) is raised up against hammer C; then slide F is run up and lever B dropped into its place and firmly fastened by thumb-screw h. Screw-driver j is set in a groove in handle A on opposite side of brad-awl (or gimlet) i, and works in the same manner as shown by brad-awl (or gimlet) i, as herein described.

That which I claim as my invention, and desire to secure by Letters Patent, is—

The tool, as above described, operating in the manner and for the purpose set forth.

GILBERT J. FERRISS.
